UNITED STATES PATENT OFFICE.

JOSEPH A. GUYER, OF MARION, INDIANA, ASSIGNOR OF ONE-HALF TO HARRY F. ANDERSON, OF MARION, INDIANA.

THERMOSTATIC REGULATOR.

Application filed March 30, 1925. Serial No. 19,523.

To all whom it may concern:

Be it known that I, JOSEPH A. GUYER, a citizen of the United States, residing at Marion, in the county of Grant and State of Indiana, have invented a certain new and useful Thermostatic Regulator, of which the following is a specification.

This invention relates to thermostatic regulators and especially to one which involves a timing or counting device, that acts also as a safety device when necessary for cutting off the heat being supplied. The invention is especially applicable to ovens wherein a certain degree of heat is required and wherein it may be required only for a certain time.

One of the objects of the invention is to provide an improved device operable to control the heat supply by the expansion and contraction of a thermal element.

Another object of the invention is to provide in said device a timing feature operable to limit the number of times that the regulator acts and to assure that the device ceases operation with the heat cut off.

Various other objects and advantages of the invention will be apparent from the following detailed description taken in connection with the accompanying drawings in which

Figure 1 illustrates the face of the device showing a control dial thereon.

Fig. 2 is a detailed view of the device showing the spring motive means.

Fig. 3 is a cross sectional view of the device showing the assembly arrangement of the parts.

Fig. 4 is a cross sectional horizontal view on the line 4-4 of Fig. 3.

Fig. 5 is a detail view of the mounting of one of the parts, the view being taken on the line 5-5 of Fig. 3.

While I have shown in the drawings and will herein describe in detail the preferred embodiment of the invention, I desire to have it understood that this disclosure is given for the purpose of representing but one specific way of carrying out the invention and is not intended as a limitation thereof to the construction disclosed. I aim to cover in the appended claims all modifications and alternative constructions falling within the scope of the invention as limited by the state of the prior art.

In the drawings I show the device attached

to an electric cooker, the device, of course, being particularly adapted for this purpose and being admirably suited for its requirements. Electric cookers are constructed to give a much higher degree of heat than is ordinarily required so that on initial heating the oven rapidly comes up to temperature permitting current to be cut off, whereafter the oven gradually cools down slowly because of its insulating construction. For long-time cooking, as for roasts and the like, it may be necessary to turn the heat on and off several times to maintain the oven at the proper temperature for a sufficiently long time. In other cases but one cut-off of the heating current may be sufficient. The present device is arranged to be set for a predetermined number of cut-offs which are roughly proportional to the time required for cooking some particular food. This permits one to place the food in the oven, to set the device and to leave it without further thought or attention.

The device in the drawings is contained in a box 6 which is fastened to one side of an oven 7. An expandible thermal element is provided and arranged to be heated by the heat in the oven and to operate the heat controlling electric switch. In the present instance the thermal element is a vent pipe 8 through which heat escapes from the lining of the oven. The thermal element is a tubular member having a right angled end 9 secured by a flange 10 to the back of box 6 and communicating with the oven interior through the passage 11. The vent pipe has its other end free and unsecured, being provided with a laterally extending open tube 12 near the free end. Tube 12 projects through an opening 12^a in the front of the box 6. The free end carries a contact tip 13 thereon which, of course, moves longitudinally with reference to the fixed end of the vent pipe as it expands and contracts. A stop member in the form of a lever 14 is pivoted at 15 adjacent the tip 13, the lever being moved by a spring 16 tending to hold it constantly against the tip 13 as the pipe 8 expands and contracts in length by the change in the temperature of the oven.

The tube 8 is arranged to cut off the current when expansion has taken place to a predetermined point and likewise to turn on the current when contraction to another predetermined point has taken place. In the

- present instance the electric switch provided is contained in an insulating casing 17 of bakelite or other suitable material, the switch being secured within the circuit box.
- 5 6. A fixed contact 18 is mounted in the bottom of the switch casing and a movable contact 19 is mounted in the top of the switch casing. Wires 20 lead to these contacts. Contact 19 is carried by a plunger 21 movably mounted in the cover 22 of the switch casing. A coil spring 23 surrounds the plunger, is connected to one of the wires 20 at the binding post 24, and operates to move the contacts into electrical engagement. A short length of insulating material in the form of a link 25 connects the plunger to a bar 26 pivoted at 27 to a metallic strip 28 secured to the box and oven. Link 25 has two holes 29 and 29^a therein adapted for pivotal connection to the bar 26. When hole 29 is used the contacts may be emersed in oil to quench the arcing caused by separating the contacts. When hole 29^a is used the contacts do not meet and a quantity of mercury or mercury and oil may be used in the switch case to provide a mercury switch if this is desirable.
- 10 The means provided to operate the switch in the present instance is a motive means tending to move past the lever 14 and constrained thereby against motion. Upon a motion in the proper direction of the lever 14 as required by the heat status of the oven, the lever permits motion to operate the switch. In the present instance, the motive means comprises a combined motor, cam, and ratchet embodied all in a single wheel 30 rigid with a shaft 31. The wheel has a plurality of ratchet teeth of two types 32 and 33 placed alternately about the periphery of the wheel 30. Teeth 32 are longer in a radial direction than the teeth 33 and have circular grooves 34 in lateral faces of the teeth on one side of the wheel. The lever 14 has a projecting end or pin 35 which rests normally against the ratchet teeth in such a manner that upon contraction of the thermal element it may pass through the grooves 34 to the next tooth 33 having no groove. When the pin 35 moves away from the tooth 33 upon expansion of the thermal element it permits the wheel 30 to move bringing the longer tooth 32 against the lever pin or end 35.
- 15 55. A cam groove 36 is formed in the wheel for operating the switch as the wheel is thus moved tooth by tooth. A tooth 32 is positioned against the end of the lever 14 when the switch is opened and a tooth 33 is positioned at the end of the lever when the switch is closed. A cam roller 37 on the bar 26 follows the groove to operate the switch. In the present instance there are sixteen teeth corresponding to eight teeth for opening and eight teeth for closing the switch

so that the cam contour repeats with alternate teeth. A clock spring 38 secured at one end to the shaft 31 and at the other end to the back of the circuit box as at 39 serves to actuate the wheel 30 counterclockwise in Fig. 3.

60 A timing or counting device is provided to limit the number of times which the regulator will turn the heat on and off. The device is capable of manual setting to limit the number of times the heat is turned on and off. As this is controlled by the temperature of the oven, which is in turn dependent upon its heat radiating properties, it follows that for any particular oven the counting device is primarily a timing device.

65 The shaft extends through the circuit box 40 and is provided with a crank handle 41 movable over a dial 42 (Fig. 1). The dial is formed by holes indicated on the dial by the numerals 1 to 8 corresponding to the position of the handle in the eight off positions of the wheel 30. Position "8" 70 on the dial 41 has a permanently mounted pin 42 thereat so that after the eighth shut-off no further action will take place, the pin 42 limiting the rotary motion of the wheel 30 by stopping the crank 40. A second pin 43 may be positioned in any 75 hole of the dial and is herein shown located in position "4" so that after the corresponding number of shut-offs (in the present instance four) the device will cease operation.

80 To operate the device one merely puts pin 43 into the hole corresponding to the time required for cooking. Suppose for this particular oven, one shut-off takes place every fifteen minutes and that about one hour is required for cooking. Then the operator will place the loose pin 43 in position "4" on the dial and turn the crank 40 clockwise against the stop pin 42 thus 85 winding the spring 38. The spring 16 permits the ratchet teeth to move lever 14 out of the way in the winding process. Current will be on in this position of the lever. When the thermal element 8 expands it will 90 push lever 14 away from the under side of tooth 33 whereupon wheel 30 will turn bringing the longer tooth 32 against the end of the lever at the same time opening the circuit through the action of the cam groove 36 upon the cam bar 26. As the oven cools 95 down the thermostatic element 8 contracts and the spring 16 draws the lever 14 inwardly toward the center of the wheel thus causing the end 35 of the lever to approach the groove 34 in the tooth which is resting 100 against the end of lever 14. When sufficiently contracted so that the end of the lever enters the groove 34, the wheel is free 105 to rotate, bringing a tooth 33 against the end of the lever and closing the circuit through the switch and cam connections.

As the oven heats up and cools down there will have been four periods of heating and four cut-offs in the current. After the fourth cut-off the handle 40 will lie against 5 the pin 43 thus preventing further operation of the device. It will be noted that the holes in the dial are so positioned that the device always comes to rest in the "off" position of the electric switch so that when 10 the predetermined time of cooking has elapsed the device will automatically shut off and require no attention on the part of the operator for this purpose.

It may frequently happen that the operator fails to insert the pin 43 in the hole required therefor and after starting the device fails to return. This, of course, leaves the device free for continuous operation for at least eight cut-offs of the 20 current. If the device operates for fifteen minutes on one heating there will never be more than two hours during which the oven will be in operation because of failure of the operator to attend to the same. Thus, 25 the pin 42 serves as a safety device for the apparatus.

In the above illustration while I have shown an electric switch as the means for controlling the supply of heat, it is obvious 30 that this may be connected to operate an electric or other source of heat and that it may be substituted by other means so that the mere action of the cam bar 26 instead of operating the switch will serve to cut in 35 or out any heat supply which it is preferable to use. Likewise, it will be understood that the length of the thermostatic element may be varied as well as its relation to lever 14 so as to control the degree of 40 heat required. But it will be understood that these improvements are well known expedients which I have not deemed it necessary to embody in the present disclosure.

I claim as my invention:

45 1. A heat regulator comprising, in combination, an electric switch operable to control a supply of heat, a thermal expansion element affected by the heat supply, a lever arranged to be moved by said thermal element as it contracts and expands, resilient means holding said lever against said element, a ratchet wheel having teeth adapted to rest against said lever, said ratchet having two sets of teeth, one set being longer 50 radially than the other and said long teeth having a channel therein to permit the passage therethrough of the end of said lever, means to rotate the wheel, a cam on said wheel, and a cam bar to operate the switch, said cam being arranged to throw the switch when the wheel moves the distance of one tooth.

60 2. A heat regulator comprising, in combination, an electric switch operable to control the supply of heat, a thermal expansion

element affected by the heat supply, a lever arranged to be moved by said thermal element as it contracts and expands, resilient means holding said lever against said element, a ratchet wheel having teeth adapted 70 to rest against said lever, said ratchet having two sets of teeth, one set being longer radially than the other and said long teeth having a channel therein to permit the passage therethrough of the end of said lever, means to rotate the wheel, a cam on said wheel, a cam bar to operate the switch, said cam being arranged to throw the switch when the wheel moves the distance of one tooth, and means to limit the number of 75 tooth spaces moved by said wheel.

3. A heat regulator for an oven and the like comprising, in combination, a thermostat, a movable member, means to move said member, ratchet teeth on said member, a stop member engaging said ratchet teeth and arranged to be moved by the thermostat, alternate teeth on said movable member projecting beyond the other teeth and having a groove therein inwardly thereof, whereby 80 the stop member may pass relatively by the short teeth and through the groove of the long teeth, and means operated by said movable member to shut off and turn on alternately a heat supply with the advance of one tooth.

4. A heat regulator for an oven and the like comprising, in combination, a thermostat, a movable member, means to move said member, ratchet teeth on said member, a stop member engaging said ratchet teeth and arranged to be moved by the thermostat, alternate teeth on said movable member projecting beyond the other teeth and having a groove therein inwardly thereof, whereby 95 the stop member may pass relatively by the short teeth and through the groove of the long teeth, a cam on said movable member to shut off and turn on alternately a heat supply with the advance of one tooth.

5. A heat regulator for an oven and the like comprising, in combination, a thermostatic element, a lever moved by said element, a movable element, two sets of ratchet teeth arranged to hold the member against motion past said lever, said teeth being further arranged so that motion of the lever to permit passage of a tooth in one set brings the lever against a tooth in another set, and means operated by said movable member to open a heat supply upon release of a tooth of one set and to close said heat supply on the release of a tooth of the other set.

6. A heat regulator for an oven and the like comprising, in combination, a movable member, means to move said member, two sets of ratchet teeth on said member, a thermostatic element arranged on contraction

and expansion to release a ratchet tooth of one set and to hold a ratchet tooth of the other set whereby the movable member advances tooth by tooth, an electric switch, 5 and means to operate said electric switch with each advance to open and close an electric circuit controlling a heat supply.

7. In a device of the class described having a spring actuated member rotating step 10 by step and arranged to turn on and off the heat supply to maintain a prolonged heat, a handle on said member, a dial over which said handle moves, said dial having a plurality of holes therein positioned in the 15 path of the handle in the off condition of the heat, and a pin adapted to be inserted in any one of said holes to limit the number of operations for stopping the device with the heat shut off.

20 8. In a device of the character described, a ratchet wheel having two kinds of teeth thereon arranged alternately, the teeth of one set projecting beyond the tips of the teeth of the other set and having therein a 25 groove, a member arranged to hold said ratchet teeth against motion said member being adapted to move out of the way of the short teeth and to move into the groove of the long teeth to permit motion of the 30 wheel.

9. In a device of the character described, a ratchet wheel having two kinds of teeth thereon arranged alternately, the teeth of one set projecting beyond the tips of the 35 teeth of the other set and having therein a groove, a member arranged to hold said ratchet teeth against motion, said member being adapted to move in one direction out of the way of the short teeth and to move 40 back into the groove of the long teeth to permit motion of the wheel, an electric switch, and a cam on said wheel arranged to effect opening and closing alternately of said electric switch as the wheel advances 45 past said member, the current controlled by said switch being effective to cause motion of the movable member.

10. In a device of the class described having a thermostat and a heat-controlling electric switch, in combination, movable means 50 associated with said thermostat and switch, said means being moved at each instance of heat-cutting-off action, and means associated with said movable means adapted to 55 limit the number of heat-cutting-off actions of said switch to a predetermined number more than one.

11. A heat regulator for an oven comprising, in combination, a thermostat, an electric switch for controlling the heat 60 affecting said thermostat, motive means interposed between the switch and the thermostat to operate the switch according to the conditions of the thermostat to maintain a given heat, and means to limit the operation 65 of said motive means to more than one heat-cutting-off operation of the switch.

12. A heat regulator for an oven comprising, in combination, a thermostat, an electric switch for controlling the heat 70 affecting said thermostat, motive means interposed between the switch and the thermostat to operate the switch according to the conditions of the thermostat to maintain a given heat, means to limit the operation 75 of said motive means to more than one operation of the switch, and means to effect stopping of the motive means in the off position of the heat.

13. A heat regulator for an oven and the like comprising, in combination, a thermostatic element, a movable stop-member controlled by said element, a motive device, two sets of teeth arranged on said motive device to hold said device against motion past the stop-member, said teeth being further arranged so that motion of the stop-member to permit passage of a tooth in one set brings the stop member against a tooth in the other set, and means controlling a heat 80 supply affecting said thermostatic element, said means being controlled by one of said movable parts to open said heat supply upon release of a tooth in one set and to close said heat supply on release of a tooth in the other 85 set.

14. A heat regulator for an oven and the like comprising, in combination, a thermostatic element, a movable stop-member controlled by said element, a motive device, two sets of teeth arranged on said motive device to hold said device against motion past the stop-member, said teeth being further arranged so that motion of the stop-member to permit passage of a tooth in one set brings the stop member against a tooth in the other set, means controlling a heat supply affecting said thermostatic element, and counting means arranged to be set for limiting the 90 number of teeth released after any one setting.

In testimony whereof, I have hereunto affixed my signature.

JOSEPH A. GUYER.
